ARTHUR D. PRATT, OF SUMMIT, NEW JERSEY, ASSIGNOR TO THE BABCOCK & WILCOX COMPANY, OF BAYONNE, NEW JERSEY, A CORPORATION OF NEW JERSEY.

SYSTEM OF VARIATION BETWEEN SIZES OR CLASSES OF SEMIVERTICAL CURVED-TUBE BOILERS.

1,363,915.

Specification of Letters Patent. Patented Dec. 28, 1920.

Application filed November 13, 1917. Serial No. 201,848.

To all whom it may concern:

Be it known that I, ARTHUR D. PRATT, a citizen of the United States, residing at Summit, in the county of Union and State 5 of New Jersey, have invented a certain new and useful System of Variation Between Sizes or Classes of Semivertical Curved-Tube Boilers, of which the following is a specification.

10 The invention will be understood by reference to the accompanying diagrammatic drawings in which Figure 1 is a composite of thirteen classes of one of the known types of semi-vertical tube boilers as now manufactured; Fig. 2 a diagrammatic view illustrating four classes following the system of variation of the present invention; and Fig. 3 a diagrammatic view to illustrate the identity of length of curvature of the 20 tubes of any class.

The general design of the semi-vertical curved tube boiler comprises two or more, preferably three, transverse steam and water drums, set parallel, and connected to a 25 mud drum by water tubes so curved as to enter the tube sheets radially. The steam space and the water space of the center drum are interconnected to the corresponding spaces of both the front and rear steam 30 drums by a row or rows of steam and water circulating tubes. The main steam outlet is placed on the top of the center or rear steam drum.

While adhering to this general design it 35 was found necessary by the original manufacturer of this type of boiler to devise variations from the first class of boiler offered. At first these variations were necessary to meet specific space conditions, that is, a 40 number of classes of boiler of the type in question were designed to fit into given spaces in existing boiler rooms: later a still further increase in the number of variations was necessary to take care of new 45 types of stokers being introduced and the development and improvement in burning different classes of fuel. This practice has been consistently followed and the variations from the original boiler offered have

50 so increased that one manufacturer has at the present time, not including numerous special classes, 18 standard classes listed. While the same general design of transverse steam and water drums connected by curved

tubes was followed in all of these classes, no 55 consideration appears to have been given to a logical variation from the class originally offered or between classes later developed. In creating new classes, the relative location of drum centers, which determine the length 60 and inclination of the tubes, appears to have been arbitrarily selected, at first to meet specific space conditions, and later to meet conditions required for the size and form of furnace necessary for a given type of stoker, 65 or required for a given class of fuel. With the drum centers for a new class of boiler determined on such a basis, and the lengths of tubes thus approximately fixed, for a boiler of a given width, such width being 70 determined either by the space conditions or the furnace requirements, the variation in amount of heating surface was obtained by supplying different numbers of tubes per section of boiler width. 75

The ultimate result of this practice is partially indicated by Fig. 1 which illustrates compositely the drums and tube outlines of thirteen of the existing eighteen classes listed by one manufacturer of this type of boiler. 80 In but two of the eighteen classes are the tubes of the same length. In all of the classes there are 226 different lengths of long tubes, and the number of such tubes per section varies in the different classes from nine to seventeen. The diameters of both steam and mud drums vary in the different classes, there being in all four diameters used in seven different combinations. The relative location of drum centers is different in all 90 but three of the classes, and due to this fact the inclination of the different banks of tubes in the various classes is different. The variation in relative location of drum centers and the difference in drum diameters used 95 necessitates a great variation in the lengths of bend necessary. In the 226 lengths of long tubes used in all classes approximately 440 lengths of bend are necessary.

Reference to Fig. 1 will make clear the 100 illogical method hitherto used in obtaining variation between classes of the semi-vertical curved tube design of boiler. One of the classes represented, designed to meet certain conditions of space, heating surface and furnace form, comprises the steam drums 4, 4^a and 4^b of a given diameter, connected by corresponding banks of tubes 5, 5^a and 5^b having 105

a given length and inclination, to a mud drum of the size indicated by the numeral 1. Another class comprises the steam drums 6, 6^a and 6^b, in which the tubes of the corresponding banks 7, 7^a and 7^b are longer than those of the class above referred to and have a different inclination to the mud drum to meet other required conditions. These tubes are connected to a mud drum of the size indicated by the numeral 2. Still another class comprises the steam drums 8, 8^a and 8^b, a mud drum of the size indicated by the numeral 3, and the corresponding connecting banks of tubes 9, 9^a and 9^b, which are longer than either of those above referred to and have a different inclination to the mud drum. I have merely selected these three classes from the large number shown, as typical, and it will be readily seen that no logical method of variation between classes was followed, but, as above stated, each class was designed to meet a given condition as to space, heating surface or other factor.

Among the disadvantages of obtaining variation between classes of this type of boiler, as now practised, may be mentioned the following: absolute lack of standardization. The completed drums drilled with their tube holes of no two of the eighteen classes are interchangeable. While certain of the classes are alike in drum diameters the relatively different location of drum centers, and the different number of tubes in the different banks means entirely different tube hole drillings. This fact makes it impracticable, from a manufacturing standpoint, to make up these drums complete except on specific order.

The great number of tube lengths necessary to meet the requirements of all classes—226 different lengths in the case of the manufacturer cited above—means an excessive tube stock to be carried. The labor involved in the shop due to the number of lengths of tube bends—approximately 440 in the case of the manufacturer above cited—will also be greatly in excess of that required under a system of variation between classes which would materially reduce such number.

The purpose of the present invention is to provide a logical system by which variation between sizes or classes of semi-vertical curved tube boilers may be obtained by a variation in but one of the features of design of this type of boiler, namely, in the length of the straight portion of the tube. The proposed system is illustrated in Fig. 2. This figure illustrates four classes or sizes of boiler in which the numeral 10 designates the mud drum common to all classes, while the numerals 11, 11^a and 11^b; 12, 12^a and 12^b; 13, 13^a and 13^b; and 14, 14^a and 14^b designate the steam drums of the smallest to the largest class respectively. The variation between sizes or classes is obtained

by moving the steam drums toward or away from the mud drum in planes parallel to their respective banks of tubes. Although I have indicated but four classes it is obvious that the system can be extended indefinitely and, whatever the number of classes, the inclination of the different banks of tubes to the mud drum and their respective steam drum will be the same. While Fig. 2 shows five tubes, five tubes and six tubes in the rear, middle and front banks respectively, the system is applicable whatever the number of tubes per bank. While Fig. 2 shows the steam drums of any one class on the same horizontal line, the system is applicable regardless of the relative vertical location of the steam drums of any one class. Fig. 2 will indicate that the mud drum, 10, as to diameter and tube hole drilling is alike for all classes regardless of the number. Likewise the front, center and rear steam drums are alike in diameter, and the tube hole drilling will be such that the front drum may be used as the front drum of any class regardless of the number; the center drum may be used as the center drum for any class regardless of the number, and the rear steam drum may be used as the rear drum of any class regardless of the number. The system permits of the same length of curvature or bend, 15, of the upper end, and the bend, 16, of the lower end of the front tube of the front bank is the same for that row of tubes for all classes regardless of the number of classes. The same holds true for all of the other rows of tubes of all the banks, each row having its individual length of curvature or bend, but being the same in the same row of all classes regardless of the number of classes or the number of tubes per bank of any class, the only difference being in the length of the straight portion of such tubes. This feature of my invention is illustrated in Fig. 3 in which the tubes *a* and *b* may be taken to represent the tubes of the first and second rows of the front bank of the smallest size of boiler, that is, the boiler having the steam drums 11, 11^a and 11^b; and the tubes *c* and *d* to represent the first and second rows of the front bank of the next larger size of boiler, that is, the one having steam drums 12, 12^a and 12^b. The length of curvature or bend of the upper ends of these tubes is represented by the angles *a'*, *b'*, *c'* and *d'* respectively, it being noted that the angles *a'* and *c'* are the same, and the angles *b'* and *d'* are the same, and that the only difference in the corresponding tubes of the two classes is in the length of their straight portions, that is, taking the line *S*, in Fig. 3 as the length of 130

the straight portion of the first row of tubes of the front bank, the increase in length of the straight portion of the first row of tubes of the front bank of the next larger class is 5 represented by the line A; and the total length by the line L.

This rule holds true as to the tubes of corresponding rows whatever the size of the class, that is, the tubes 15, 17, 18 and 19, all 10 being tubes of the first row of the front banks of the four classes shown in Fig. 2, have the same curvature or bend at their upper ends, the only difference being in the lengths of their straight portions. Similarly the tubes 20, 21, 22 and 23, being the tubes of the second row of the first bank, have the same curvature or bend at their upper ends, the only difference being in 15 lengths of their straight portions.

20 While the system of variation between classes may be extended indefinitely, the four classes shown in Fig. 2 will meet practically every requirement of horse power and space conditions that may be encountered.

25 The advantages of my system may be briefly summarized as follows.

1. The advantages from a manufacturing standpoint are those accompanying any real 30 and logical standardization.

2. But two diameters of drums are contemplated instead of four as at present used by the manufacturers of this type of boiler, thus reducing the drum plate stock that 35 must be carried.

3. The drums of any class, regardless of the number of classes, would be for a given 40 width of boiler, interchangeable. With a knowledge of the widths in the greatest demand it would be practicable, in dull times, to make up complete drums for stock, to 45 meet prompt deliveries at rush times, without involving excessive carrying charges.

4. Assuming that the four classes indicated in Fig. 2 would meet practically all 50 of the conditions of installation that will be encountered, a tube stock for all classes would consist of but 64 lengths as compared with 226 lengths under the system of variation between classes as used by the manufacturer above cited.

5. These 64 lengths of tube would require but 28 lengths of curvature or bend as against the approximate 440 lengths necessary in present practice.

6. The relative vertical location of the steam drums would not affect the proposed system.

7. Under the proposed system, any location of steam outlet, any baffle arrangement, any furnace arrangement or any superheater arrangement now in use with the semi-vertical, curved tube type of boiler could be used without altering the proposed 65 method of variation between classes.

What I claim and desire to secure by Letters Patent of the United States is:—

1. In boilers of the semi-vertical curved tube type having upwardly diverging banks of tubes, sets of standard upper transverse 70 drums and a standard lower transverse mud drum, said drums having tube holes standardized both as to size and location, in combination with standard interchangeable sets of water tubes designed to afford boilers 75 of different sizes, said sets of tubes having straight portions with curved ends arranged to be expanded in the tube holes of the standard drums, the sets differing from each other solely in the length of their 80 straight portions, whereby boilers of different sizes of the same semi-vertical curved tube type may be assembled from the same standard drums and sets of tubes of varying length having standard curvatures in their 85 curved end portions.

2. In boilers of the semi-vertical curved tube type having upwardly diverging banks of tubes, sets of standard upper transverse drums and a standard lower transverse mud 90 drum, said drums having tube holes standardized both as to size and location, in combination with standard interchangeable sets of water tubes designed to afford boilers 95 of different sizes, said sets of tubes having straight portions with curved ends arranged to be expanded in the tube holes of the standard drums, the sets differing from each other solely in the length of their straight portions, and sets of horizontally extending 100 circulating circulators arranged to connect some of the drums, said sets of circulators differing in length, but all being adapted to enter the same tube holes of the standard drums, whereby boilers of different sizes of the 105 same semi-vertical curved tube type may be assembled from the same standard drums and sets of semi-vertical tubes of varying length having standard curvatures in their 110 curved end portions.

3. The method of making boilers of semi-vertical curved tube type having upwardly diverging banks of tubes and of different horse power capacities, consisting in expanding into sets of upper and lower transverse drums, sets of water tubes having straight portions with curved ends, each of said tubes extending from the lower transverse drum to one of the upper transverse drums, corresponding tubes of the different 115 sets of tubes for boilers of different capacities differing from each other solely in the length of their straight portions between the curved end portions, and corresponding drums of the different sets for boilers of 120 different capacities having tube holes the same both as to size and location, whereby the boiler structures differ from each other solely in the lengths of the straight portions 125 of the tubes.

4. A series of semi-vertical curved tube boilers having upwardly diverging banks of tubes and of progressively increasing capacities, each boiler of the series having a plurality of upper transverse drums and a lower transverse drum with sets of tubes connecting the lower drum with each of the upper drums, each drum of each boiler in the series being identical with all of the corresponding drums of the other boilers of the series and each tube of each boiler of the series having ends identical as to curvature with all of the corresponding tubes of the other boilers of the series, the length of the straight portions of corresponding tubes of the series increasing progressively throughout the series.
5. In the art of manufacturing water-tube boilers having upwardly diverging banks of tubes and of different horse power capacities and having a plurality of transverse drums at different levels connected by banks of water tubes having curved end portions, the method which consists in preparing a plurality of sets of drums having tube holes of the same size and location, preparing a plurality of sets of tubes for different boilers, the sets differing from each other only in length, and constructing therefrom a boiler of a desired capacity by connecting into standard drums a set of standard tubes as above provided and which are

of a length between their curved end portions corresponding to the desired horse power of the boiler; whereby boilers of different horse power capacities may be made up from said parts, said boilers differing from each other solely in the length of the straight portions of the tubes of said banks.

6. In the art of making water-tube boilers having upwardly diverging banks of tubes and of different horse power capacities having a plurality of transverse drums at different levels connected by banks of water tubes having curved ends, the steps consisting of providing a plurality of sets of drums each alike as to location and size of tube holes, providing a plurality of sets of water tubes, said sets differing solely in the length of their straight portions and each set adapted to be connected to any set of said drums, and building a boiler of any desired horse power within certain limits by connecting into a set of said drums a set of said water tubes having a length selected in accordance with the boiler horse power desired.

In testimony whereof I have hereunto signed my name in the presence of two subscribing witnesses.
